GARBAGE CAN HOLDER

Frank Arnold, Jr., 415 Lindhardt Road,
Carlisle, Iowa 50017

Filed Apr. 28, 1971, Ser. No. 138,408

Term of patent 14 years

Int. Cl. D8—08

U.S. Cl. D8—234

FIG. 1 is a perspective view of a garbage can holder showing my new design;

FIG. 2 is a top plan view thereof;

FIG. 3 is a side elevation view thereof; and

FIG. 4 is a bottom plan view thereof.

I claim:

The ornamental design for a garbage can holder, substantially as shown and described.
